J. KAST,
CLAMP FOR ROPE BELTING.
APPLICATION FILED FEB. 24, 1908.

Patented Nov. 10, 1908.

UNITED STATES PATENT OFFICE.

JACOB KAST, OF BOSTON, MASSACHUSETTS, ASSIGNOR OF ONE-FOURTH TO GERHARDT H. LINDEBOOM, OF MALDEN, MASSACHUSETTS.

CLAMP FOR ROPE BELTING.

No. 903,727.

Specification of Letters Patent.

Patented Nov. 10, 1908.

Application filed February 24, 1908. Serial No. 417,603.

To all whom it may concern:

Be it known that I, JACOB KAST, a citizen of the United States of America, and a resident of Boston, in the county of Suffolk and 5 State of Massachusetts, have invented certain new and useful Improvements in Clamps for Rope Belting, of which the following is a specification.

This invention relates to endless belting 10 and particularly to that class of belting which is woven from a plurality of strands of textile material, and it relates particularly to the means for securing the ends of said belting together to form a continuous 15 belt, the inner face of which is without a break.

It consists in crossing the ends of the longitudinal strands of said belting and laying these ends parallel to one another on either 20 side of the point of crossing upon an inner section of the belting and then clamping these strands effectually to said inner sections by devices which engage with the outer layer of strands of the inner section of belting, thus leaving a portion of the strands 25 beyond the limit of the fastening devices and interposed between the same and the face of the pulley when in operation.

The invention further consists in certain 30 novel features of construction and arrangement of parts which will be readily understood by reference to the description of the drawings and to the claims hereinafter given.

35 Of the drawings: Figure 1 represents a plan of a portion of an endless belting connected together by my improved device, one of the plates being shown removed therefrom and the securing staples therefor cut in 40 section, the cutting plane being on line 1—1 on Fig. 2. Fig. 2 represents a vertical section of the same, the cutting plane being on line 2—2 on Fig. 1. Fig. 3 represents a transverse section of the same, the cutting 45 plane being on line 3—3 on Fig. 2, and Fig. 4 represents a transverse section of the same, the cutting plane being on line 4—4 on Fig. 2.

Similar characters designate like parts 50 throughout the several figures of the drawings.

In the drawings, 10 represents a portion of woven belting made up of a plurality of strands 11 and 12 which cross each other at 55 13 and are connected together by means of

the cross strands 14. At each end of the belting 10 the cross strands 14 are terminated at 15 while the longitudinal strands 11 and 12 extend for a short distance beyond, as at 16 in Figs. 1 and 2, forming disconnected ends terminating at 17. These disconnected ends 16 cross one another at 18 and rest upon one section of the belting the strands of which are connected together by means of the cross strands 14.

60 On either side of the point of crossing 18 and resting upon the disconnected strands 16 are the plates 19 provided with the downward turned lips 20 which embrace the disconnected ends 16 and prevent them from spreading outwardly when strain is brought to bear thereon. Each of the plates 19 is 65 provided with a plurality of staples 21 in four rows, said staples being staggered with the staples in one row overlapping the staples in the next adjacent row. The outer ends of the staples 21 are threaded and upon these ends the nuts or other adjusting devices 22 operate. The cross member of each staple 21 is flattened as at 23 and passes beneath a plurality of strands 11 or 12, the plurality of staples in two adjacent rows 70 acting upon all of the strands 11 while similar staples in the other two rows of each plate operate upon all of the strands 12. 75 By this means each one of the strands 11 and 12 in each section of belting is clamped firmly and effectually against the disconnected ends 16 of the strands of the opposite section and these in turn are clamped against 80 the plate 19.

A greater tension may be brought to bear 85 upon the various parts to more firmly clamp them in position by means of the nuts 22 which may be moved along the threaded 90 ends of the staples 21 for this purpose. It is obvious that from an inspection of the drawings a thickness of fibrous material is 95 interposed between the staples 21 and the face of any pulley on which the belting is 100 adapted to be used. The plates 19 are prevented from slipping longitudinally of the belt 10 by means of their ends abutting one another and the staples 21 therein being immediately on either side of the point of 105 crossing of the disconnected strands 16.

By such a construction as this a most effectual clamp is made for connecting the ends of such a belting as is herein shown, leaving the inner face or contacting face per- 110

fectly even throughout its entire surface while the ends are so firmly and effectually locked together that there is no opportunity for separation at this point.

5 In the drawings the belting is shown opened up and somewhat exaggerated in order to more clearly illustrate the invention.

It is believed that from the foregoing the operation and advantages of this invention 10 will be fully understood.

Having thus described my invention, I claim:

1. The combination of a woven belting; a plate; a plurality of staples therein adapted 15 to engage all the longitudinal strands of one end of said belting and grip between them and said plate the strands of the opposite end; and adjusting devices coöperating with said staples.

20 2. The combination of a woven belting; a plate; a plurality of staples therein staggered in relation to each other; and adjusting devices coöperating with said staples.

3. The combination of a woven belting; 25 two plates; a plurality of staples in each plate adapted to engage all the longitudinal strands of one end of said belting and grip between them and said plate the strands of the opposite end; and adjusting devices co- 30 operating with said staples.

4. The combination of a woven belting; two plates, said plates abutting one another; a plurality of staples in each plate adapted 35 to engage all the longitudinal strands of one end of said belting and grip between them and said plate the strands of the opposite end; and adjusting devices coöperating with said staples.

5. The combination of a woven belting; 40 two plates; a plurality of staples in each plate, said staples in one plate being adapted to grip the strands in an intermediate section of one end of the belting while those in the other plate are adapted to grip the strands of 45 an intermediate section of the other end of

the belting; and adjusting devices coöperating with said staples.

6. The combination of a woven belting; two plates each provided with a plurality of staples in a plurality of rows overlapping each other; and adjusting devices on said staples, the staples of each plate being adapted to pass through the center of an intermediate section of one end of the belting and grip between it and said plate the extreme 55 ends of the strands at the other end of said belting.

7. The combination of a woven belting, the strands at each end of which are crossed and laid flat upon an intermediate section of 60 the other end of the belting; and a connector consisting of means connected with the outer layer of each of said intermediate sections for effectually locking said strands of the other end thereto. 65

8. The combination of a woven belting, the strands at each end of which are crossed and laid flat upon an intermediate section of the other end of the belting; a plate on each side of said crossing of the strands adapted 70 to rest upon said strands; and means secured to said plate for effectually locking said strands to the intermediate section on which they rest.

9. The combination of a woven belting, 75 the strands at each end of which are crossed and laid flat upon an intermediate section of the other end of the belting; a plate on each side of said crossing of the strands adapted to rest upon said strands; and a plurality of 80 staples secured to said plate for effectually locking said strands to the intermediate section on which they rest.

Signed by me at 7 Water St., Boston, Mass., this 20th day of February, 1908.

JACOB KAST.
